UNITED STATES PATENT OFFICE.

WILLIAM S. HAMM, OF HUBBARD WOODS, ILLINOIS, ASSIGNOR TO THE ADAMS & WESTLAKE COMPANY, A CORPORATION OF ILLINOIS.

WINDOW-SASH AND WEATHER-GUARD THEREFOR.

1,102,403.

Specification of Letters Patent.

Patented July 7, 1914.

Application filed March 25, 1912. Serial No. 686,027.

To all whom it may concern:

Be it known that I, WILLIAM S. HAMM, a citizen of the United States, and resident of Hubbard Woods, county of Cook, and State 5 of Illinois, have invented certain new and useful Improvements in Window-Sashes and Weather-Guards Therefor, of which the following is a specification, and which are illustrated in the accompanying drawings, forming 10 a part thereof.

The invention relates to window sash and weather guards therefor, being especially adapted for use in connection with car windows; its object being to provide a simple, 15 inexpensive and efficient guard for excluding drafts, dust and moisture at the side edges of the sash.

In the accompanying drawings illustrating the invention—Figure 1 is a detail plan 20 section of a window casing, a pair of sashes and the weather guard; Fig. 2 is a sectional detail in perspective of the side rail of the sash; Fig. 3 is a sectional detail in perspective of the weather guard; and Fig. 4 is a 25 sectional detail in perspective of the retaining strip for the weather guard.

The invention may be used in connection with any form of window casing, there being shown a casing 10 having an adjustable stile 30 plate 11, an inner sash stop 12, and an intermediate sash stop 13. There is shown in the drawings an inner sash 14 and an outer sash 15, the side rails 16, 17, thereof being of wood, their width being such that they do 35 not enter the runways between the casing stops. These side rails are longitudinally grooved, as shown at 18, and to the outer face of each the weather guard is applied.

This weather guard, indicated as a whole 40 by the numeral 19, is formed of a sheet of spring metal, the central portion of which conforms to the outer edge of the sash, being provided with a rib 20 for entering the groove 18. The plate extends outwardly beyond each face of the sash rail, its marginal portions being bent inwardly so as to give the plate, broadly speaking, a U shape. The side arms of the U, designated by the numerals 21, 22, normally incline outwardly 45 with reference to the plane of the adjacent side face of the sash rail. Preferably each of the wings thus formed is united with the transverse portion of the plate by an outwardly bowed section 23, 24, for increasing 50

its resiliency and covering the edge of the 55 stop with which it co-operates.

A retaining strip 25 is applied to the edge of the sash rail, fitting against the transverse member of the weather guard and being provided with a longitudinal rib 26 for entering 60 the rib 20 thereof. The strip 25 is secured to the sash by any suitable means, such as screws 27, which pass through suitable apertures, as 28, in the weather guard. The strip 25 is preferably of less width than the 65 thickness of the rail 16, thereby leaving a space between each of its side faces and the adjacent stop, within which the wings 21, 22, of the weather guard are located.

When the sash is in place the wings of the 70 weather guard bear outwardly and with a spring pressure against the stops, and thus effectually exclude air currents, dust and moisture while leaving the sash free to slide within the ways. Preferably the strip 25 is 75 of such thickness that it is in sliding engagement with the face of the stile plate 11, so as to prevent rattling of the sash, while the length of the wings 21, 22, is such that they do not make contact with the stile plate. 80

While the weather guard is shown as formed of a single plate, it is obvious that a portion of the cross member might be omitted, the wings being provided with instanding flanges clamped between the strip 25 and 85 the edge of the sash.

I claim as my invention—

1. In a window sash and weather guard therefor, in combination, a side rail, a retaining strip secured to the edge of the rail, 90 and adapted to engage the stile face of a casing a spring metal plate located at the side of and spaced apart from the strip and having a flange clamped between the strip and the sash rail. 95

2. In a window sash and weather guard therefor, in combination, a side rail, a U-shaped plate of spring metal fitted to the edge of the rail, its marginal portions projecting outwardly from the rail and being 100 inclined away each from the other, and a retaining strip for clamping the plate to the rail and projecting beyond the edges of the marginal portions of the plate.

3. In a window sash and weather guard 105 therefor, in combination, a side rail having a longitudinal channel in its outer edge, a spring metal plate fitted to the edge of the

2
rail and having a rib entering its channel, the marginal portions being folded to the planes of the side faces of the rail but inclined outwardly from such planes, and a retaining strip of less width than the thickness of the rail and secured to the edge thereof over the metal plate and projecting beyond the edges of the marginal portions of the plate.

10 4. In a window sash and weather guard therefor, in combination, a side rail having a longitudinal channel in its outer edge, a spring metal plate fitted to the edge of the rail and having a rib entering its channel,

the marginal portions being folded to the planes of the side faces of the rail but inclined outwardly from such planes, and a retaining strip of less width than the thickness of the rail and secured to the edge thereof over the metal plate and having a longitudinal rib entering the rib of the plate such strip extending beyond the edges of the marginal portions of the plate.

WILLIAM S. HAMM.
